UNITED STATES PATENT OFFICE

2,156,285

WRENCH

Clarence E. Harris, Winthrop, Mass.

Application August 2, 1937, Serial No. 156,993

1 Claim. (Cl. 81—119)

(Granted under the act of March 3, 1883, as
amended April 30, 1928; 370 O. G. 757)

The invention described herein may be manufactured and used by or for the Government for governmental purposes, without the payment to me of any royalty thereon.

5 The subject of this invention is a wrench.

The purpose of the invention is to provide a wrench for a special situation in which there is not sufficient space to apply a large force to turn the wrench.

10 The invention consists in providing a wrench with a pivotally mounted extension having a plurality of selectively engageable members on which to apply the force of a lever.

Several embodiments of the invention are illustrated in the accompanying drawing in which:

15 Fig. 1 is a view of a structure having a limited space and showing the employment of the wrench forming the subject of the invention.

Fig. 2 is a detail view in side elevation of the wrench.

20 Fig. 3 is a view in end elevation.

Fig. 4 is a view of a chain-type extension.

Referring to Fig. 1 there is shown a structure which is part of the recuperator mechanism of a 25 gun and which includes a member 5 which is to be secured by a plurality of nuts or bolts 6 of some of which are so located that the space for operation of a wrench 7 is exceedingly restricted.

According to this invention, the wrench is provided with an extension, which, in the form shown in Figs. 1 to 3, consists of a rigid bar 8 which is connected to the handle of the wrench by means of a pivot pin 9. The greater portion of the bar 5 is in the shape of a ladder, the openings 10 providing for passage of a rod 11 and the crosspieces 12 adapted to be engaged by the rod. The rod is used as a lever, with one end engaging one of the bolts 6 which serves as a fulcrum, and in this 10 manner a considerable force may be exerted on the crosspieces 12 to effect turning of the wrench.

In the modification shown in Fig. 4 the extension is a flexible member such as a chain 13 of open links which are straddled by the bifurcated 15 end of a rod 14 and which supply the surface on which the rod may act.

I claim:

A wrench including a handle with a work-engaging end, a pivot pin in the end of the handle 20 opposite to the work-engaging end, and a rigid member mounted on the pivot pin, said member having a plurality of openings and crosspieces for application of a lever and arranged parallel to the axis of the pivot pin and remote from the 25 work-engaging end of the handle.

CLARENCE E. HARRIS.
